UNITED STATES PATENT OFFICE.

CHARLES E. GOODYEAR, OF BETHEL, OHIO.

ELLIPTIC SPRING.

SPECIFICATION forming part of Letters Patent No. 770,496, dated September 20, 1904.

Application filed April 28, 1904. Serial No. 205,298. (No model.)

To all whom it may concern:

Be it known that I, CHARLES E. GOODYEAR, a citizen of the United States, and a resident of the town of Bethel, in the county of Clermont and State of Ohio, have invented an Improvement in Elliptic Springs, of which the following is a specification.

My invention is applicable to the various kinds of road-vehicles which require springs. The several features of my invention and the various advantages resulting from their use conjointly, or otherwise will be apparent from the following description and claims.

In the accompanying drawings, making part of this application, and in which similar letters of reference indicate corresponding parts, Figure 1 represents in perspective a spring embodying my invention. Fig. 2 represents the spring applied to the front of a buggy. Fig. 3 represents the spring applied to the rear end of a buggy.

It is to be understood that this spring is to be applied to any part of a vehicle-gear as may be desired and that in any suitable combination one or more such springs may be employed upon the same vehicle. Among the various modes of employing such springs other than the mode shown in the drawings may be mentioned the combination known as "platform-springs."

I will now proceed to describe my invention in detail.

A indicates the double spring, B² the upper half, and B³ the lower half thereof. Each half may consist of one or more leaves C. Other conditions of construction being the same, the increase in the number of leaves will increase the strength of the spring. The leaves are of the peculiar and novel shape shown—that is to say, the portion C⁵ of the leaf is slightly curved or approximately straight. The center C² of the spring is much depressed, and this depressed portion is preferably curved at C³. This center portion C² is united at each end to the adjacent portion C⁵ by a curve C⁴, substantially as shown.

When the double spring is employed, as shown in Figs. 1, 2, and 3, the central depression C² is preferably downward toward

the ground in both halves of the spring; but 50 the slight curve C³, when present, of this central portion curves upward in the upper half of the spring and downward in the lower half of the spring. Each half of the spring is duly secured to its appropriate part of the 55 gear by clips D or other well-known means located at the depressed center, substantially as shown. The curve C⁴ of each spring is a gentle and gradual one, and this gradual change of direction in the material of the 60 spring prevents the latter from being readily broken at such curve or bend.

The principal advantage of my improved spring is its superior elasticity. The spring possesses not only the elasticity of the arms 65 or portions C⁵, but also that of the corner or bent portions C⁴ at both the corners X and at the gradually-curved corners Y and to a certain limited extent in the central portion C².

The combined shape of the upper and lower 70 halves of the spring and the relative arrangement of their respective parts all unite to enable all the portions of the combined spring to operate harmoniously and with great uniform and properly-graduated elasticity.

What I claim as new and of my invention, and desire to secure by Letters Patent, is—

1. An elliptic or double spring, each half having a center C², and limbs C⁵, the limbs united to the center C² by the curved portion 80 C⁴, whose shoulder X is united to the center C², and whose gently-curved portion Y is united to the limb, the central portions C², C⁴, being both depressed in the same direction, substantially as and for the purposes specified. 85

2. An elliptic or double spring, each half having a depressed central portion, and adjacent limbs united to the center by a curved portion, both central portions being depressed in the same direction, substantially as and for 90 the purposes specified.

In witness whereof I have set my hand to this specification in the presence of two subscribing witnesses.

CHARLES E. GOODYEAR.

Attest:

W. M. J. RIELLY,
B. SMITH.
